UNITED STATES PATENT OFFICE.

WHITCOMB L. JUDSON, OF NEW YORK, N. Y., ASSIGNOR TO THE JUDSON PNEUMATIC STREET RAILWAY COMPANY, OF SAME PLACE.

DESIGN FOR A TOWER.

SPECIFICATION forming part of Design No. 19,437, dated November 19, 1889.

Application filed October 24, 1889. Serial No. 328,068. Term of patent 7 years.

To all whom it may concern:

Be it known that I, WHITCOMB L. JUDSON, a citizen of the United States, residing at New York city, in the county of New York and State of New York, have invented and produced a new and original Design for Towers; and I do hereby declare the following to be a full, clear, and exact description of the same, reference being had to the accompanying drawings, forming a part thereof, and in which—

Figure 1 represents in elevation the character of the design, while its form in cross-section is shown in Fig. 2.

The leading feature of my design consists of a skeleton structure tapering from its base to its top, having external galleries at different heights and surmounted by a double-tiered colonnade gallery and observatory supporting a cupola or dome.

The tower is of circular or cylindrical form in cross-section, and consists, essentially, of vertical ribs A, resting upon and extending from a suitable base B to and supporting a

double-tiered gallery C D, colonnade in style. 25 An interior spiral or winding roadway E, extending from the base to the top, unites with the ribs A at suitable distances apart as a single structure, and appears in elevation through them. At suitable distances apart 30 external horizontal galleries F are provided, having the appearance of exterior bands around the structure, while at the top a colonnade-gallery C surmounts the structure and supports a smaller colonnade-gallery D 35 or observatory, which is capped by a dome G, all presenting to the eye the combined effect of great height and symmetry of proportion.

I claim—

The design for a tower, substantially as 40 herein set forth and illustrated.

In testimony whereof I affix my signature in presence of two witnesses.

WHITCOMB L. JUDSON.
